Bjerregaard Svendsen, Copenhagen, Denmark

Application January 12, 1952, Serial No. 266,154

8 Claims. (Cl. 81—151)

1

The present invention relates to a device for the relative adjustment and frictional attachment of two members.

Such devices are known in the shape of wrenches, slidable gauges, adjustable shelving and many other constructions in which two members are movable in guided relation to each other to a predetermined position in which the members are to be relatively fixed from which they may be subsequently moved to any other desired position and fixed there.

The object of the invention is to provide a device of the kind in question which is relatively strong and at the same time substantially lighter in weight than the hitherto known devices of similar types.

Further objects of the invention will be evident from the following description taken in conjunction with the drawings, which for the purpose of illustration show a preferred construction of a wrench, but it is particularly emphasized that the disclosed features of the wrench can with the same effect be applied to any other construction in which a similar result is required.

Referring to the drawing:

Fig. 1 shows in side elevation a so-called monkey wrench, according to the invention,

Fig. 2 is a section on line II—II in Fig. 3,

Fig. 3 is a section on line III—III in Fig. 2,

Fig. 4 is a transverse vertical section on line IV—IV in Fig. 2, and

Fig. 5 shows on an enlarged scale a section view on line V—V in Fig. 3.

A handle 104 of the wrench has a rear part 105 from which extend two sides 106 and 107, each provided with an enlargement 108 and 109 respectively. Between these sides the wrench has a through-hole with rectangular cross section, and between the enlargements 108 and 109 there is a slot 110. The enlargements 108 and 109 are integral with a fixed jaw 111. A movable jaw 112 is provided with a narrow portion 113 and a wide portion 114 which latter on its end turned away from the narrow portion 113 is provided with an angular recess having a bevelled face 115 with an incline of one to two, and a bevelled face 116. Abutting the face 115 is the slightly curved surface 117 of an angular projection which has another face 118 slightly spaced from the face 116, see Fig. 5. The said projection is formed on a holder of U-shaped cross section and comprises a rear part 119 and two legs 120. The holder carries three pressure members or plates 121, 122 and 123, each of which is provided with a center portion slidable between the legs and provided

2

with upper projecting lugs 124 and 125 and lower projecting lugs 126 and 127 which engage the upper and lower edges of the legs 120 respectively.

Between the legs 120 and the pressure plates 121, 122 and 123 are inserted long plate members 128, 129 and 130, each of which has a width allowing them to slide between the legs 120. At their upper ends each plate member has an enlarged portion extending into a transverse groove in a holder 131 rigidly attached within the rectangular hole. This holder 131 has a hole for a pin 132 passing through the said grooves and through holes in each of the enlarged portions of the plate members, thus fixing these members nondisplaceable longitudinally in relation to the holder. The holder 131 has furthermore a part which fits snugly between the sides 106 and 107, and another wider recessed part resting upon the edges of the sides and thus effectively preventing the holder from being pulled downwards. The plate member 128 abuts with its one side the rear part 119 of the holder for the short pressure plates, and the short pressure plate 123 abuts with its one side the flat side of the rear part 105.

The one leg 120 of the holder has a threaded hole for the threaded end of a pin 133 which has a rigidly attached head 134 projecting outside a slot 135 with a recessed edge 136 accommodating a ring 137 that encompasses pin 133 and is pressed against the recessed face by means of a spring 138 interposed between the ring and the rear side of head 134.

When endeavouring to press the two jaws 111 and 112 away from each other with a certain force, there will be transmitted a force to the bevelled face 115 and the curved surface 117 which is about double the first mentioned force, so that the wide portion 114 and the rear part 119 are subjected to an outward lateral pressure of the same magnitude. In this manner a frictional force is produced between the short pressure plates 121, 122, 123 the long plate members 128, 129, 130 and the rear part 119, as well as between the wide portion 114 and the edges of the enlargements 108, 109. The total frictional force thus becomes so much greater than the first mentioned force applied to the jaws that a self-locking effect is attained. When hereafter the pin 133 is moved upwards, the wide portion 114 together with the movable jaw 112 will also be moved upwardly along the surface 115, since the wide portion 114 is not self-locking for such an oblique pressure. When moving the pin 133 downwards the face 118 will press against the face 116 so that the movable jaw 112 is moved

with it. The movable jaw may now be moved towards the fixed jaw 11 without using the pin 133.

We declare that what we claim is:

1. A slidable side jaw wrench with friction type wedgelock means, comprising a main body having a handle portion and a fixed jaw, and adjacent the fixed jaw two interspaced walls extending at a right angle to the clamping face of said fixed jaw and each at their edges near the fixed jaw provided with an inwardly projecting web, said webs extending at a right angle in relation to the clamping face of the fixed jaw to provide rearwardly facing guiding shoulders, and which walls remote from the fixed jaw are interconnected by means of a main body portion constituting a friction surface disposed at a right angle to the clamping face of the fixed jaw and opposing said shoulders, and which walls enclose a cavity, which is defined by the interior surfaces of said walls, the shoulders and the said friction surface and is open at the jaw side through a slot defined by said webs, a movable jaw disposed in front of the webs and integral with a guide portion extending rearwardly through said slot and provided with lateral projections engaging said shoulders; a pressure member disposed in the cavity behind said guide portion, wedging means interconnecting said guide portion and said pressure member; interspaced fixed clamping members nonslidably connected to the main body and disposed in the cavity between the pressure member and the friction surface of the cavity, movable clamping members interposed between said fixed clamping members and provided with friction surfaces extending at a right angle to the clamping surface of the fixed jaw and engaging friction surfaces of the fixed clamping members, the said movable clamping members being nonslidably connected to the movable jaw, coacting friction surfaces on the foremost fixed clamping member and the pressure member, and a movable clamping member nonslidably connected to the movable jaw interposed between the rearmost fixed clamping member and friction surface of the cavity.

2. A wrench as claimed in claim 1, in which the clamping members comprise thin lamellae, of which the fixed lamellae are nonslidably connected to the main body at their ends near the fixed jaw.

3. A wrench as claimed in claim 1, in which an operating member for shifting the movable jaw is connected to the pressure member and projects through a slot provided in one of the cavity walls.

4. A wrench as claimed in claim 1, in which the pressure member has two legs extending rearwardly between at least the foremost fixed clamping member and the cavity walls and engaging lateral projections on at least the foremost movable clamping member.

5. A slidable side jaw wrench with friction type wedgelock means, comprising a main body having a handle portion and a fixed jaw, and adjacent the fixed jaw two interspaced walls extending at a right angle to the clamping face of said fixed jaw and each at their edges near the fixed jaw provided with an inwardly projecting web, said webs extending at a right angle in relation to the clamping face of the fixed jaw to provide rearwardly facing guiding shoulders, and which walls remote from the fixed jaw are interconnected by means of a main body portion constituting a friction surface disposed at a right

angle to the clamping face of the fixed jaw and opposing said shoulders, and which walls enclose a cavity, which is defined by the interior surfaces of said walls, the shoulders and the said friction surface and is open at the jaw side through a slot defined by said webs, a movable jaw disposed in front of the webs and integral with a guide portion extending rearwardly through said slot and provided with lateral projections engaging said shoulders, a pressure member disposed in the cavity behind said guide portion, wedging means interconnecting said guide portion and said pressure member, interspaced fixed clamping members nonslidably connected to the main body and disposed in the cavity between the pressure member and the friction surface of the cavity, movable clamping members interposed between said fixed clamping members and provided with friction surfaces extending at a right angle to the clamping surface of the fixed jaw and engaging friction surfaces on the fixed clamping members, the said movable clamping members being nonslidably connected to the movable jaw, coacting friction surfaces on the foremost fixed clamping member and the pressure member, and a movable clamping member nonslidably connected to the movable jaw interposed between the rearmost fixed clamping member and friction surface of the cavity; and a spring member connected to the pressure member and arranged to exert a pressure on a surface of the main body extending at a right angle to the clamping face of the fixed jaw.

6. A slidable side jaw wrench with friction type wedgelock means, comprising a main body having a handle portion and a fixed jaw, and adjacent the fixed jaw two interspaced walls extending at a right angle to the clamping face of said fixed jaw and each at their edges near the fixed jaw provided with an inwardly projecting web, said webs extending at a right angle in relation to the clamping face of the fixed jaw to provide rearwardly facing guiding shoulders, and which walls remote from the fixed jaw are interconnected by means of a main body portion constituting a friction surface disposed at a right angle to the clamping face of the fixed jaw and opposing said shoulders, and which walls enclose a cavity, which is defined by the interior surfaces of said walls, the shoulders and the said friction surface and is open at the jaw side through a slot defined by said webs; a movable jaw disposed in front of the webs and integral with a guide portion extending rearwardly through said slot and provided with lateral projections engaging said shoulders; a pressure member disposed in the cavity behind said guide portion, wedging means interconnecting said guide portion and said pressure member; wedging means interconnecting said guide portion and said pressure member, and having a wedging inclination of about one to two; three interspaced fixed clamping members nonslidably connected to the main body and disposed in the cavity between the pressure member and the friction surface of the cavity, two movable clamping members interposed between said fixed clamping members and provided with friction surfaces extending at a right angle to the clamping surface of the fixed jaw and engaging friction surfaces on the fixed clamping members, the said movable clamping members being nonslidably connected to the movable jaw, coacting friction surfaces on the foremost fixed clamping member and the pressure member, and a movable clamping member nonslidably connected to the mov-

able jaw interposed between the rearmost fixed clamping member and friction surface of the cavity.

7. A slidable side jaw wrench with friction type wedgelock means, comprising a main body having a handle portion and a fixed jaw, and adjacent the fixed jaw two interspaced walls extending at a right angle to the clamping face of said fixed jaw and each at their edges near the fixed jaw provided with an inwardly projecting web, said webs extending at a right angle in relation to the clamping face of the fixed jaw to provide rearwardly facing guiding shoulders, and which walls remote from the fixed jaw are interconnected by means of a main body portion constituting a friction surface disposed at a right angle to the clamping face of the fixed jaw and opposing said shoulders, and which walls enclose a cavity, which is defined by the interior surfaces of said walls, the shoulders and the said friction surface and is open at the jaw side through a slot defined by said webs, a movable jaw disposed in front of the webs and integral with a guide portion extending rearwardly through said slot and provided with lateral projections engaging said shoulders; a pressure member disposed in the cavity behind said guide portion, intercoacting and correspondingly inclined wedging surfaces on the rear side of said guide portion and the front side of said pressure member; interspaced fixed clamping members nonslidably connected to the main body and disposed in the cavity between the pressure member and the friction surface of the cavity, movable clamping members

interposed between said fixed clamping members and provided with friction surfaces extending at a right angle to the clamping surface of the fixed jaw and engaging friction surfaces on the fixed clamping members, the said movable clamping members being nonslidably connected to the movable jaw, coacting friction surfaces on the foremost fixed clamping member and the pressure member, and a movable clamping member nonslidably connected to the movable jaw interposed between the rearmost fixed clamping member and friction surface of the cavity.

8. A wrench as claimed in claim 7, in which one of the wedging surfaces is convex with a rectilinear generatrice at a right angle in relation to the direction of movement of the movable jaw.
